ATTORNEY

UNITED STATES PATENT OFFICE

WALLACE M. MINTO, OF JERSEY CITY, NEW JERSEY

CARTRIDGE FOR FIREARMS

Application filed April 23, 1931. Serial No. 532,364.

The invention has relation to cartridges and particularly to tear gas cartridges containing the chemical chloracetophenone or its equivalent.

It has been ascertained through test that this chemical or any of its substitutes will decompose or deteriorate so as to be useless within a few months time unless the cartridge shell or container is lined with glass, and it is an object of this invention to provide a capsule or envelope for the chemical which will be instantly destroyed as an entirety by the explosion of the shell in the gun, thereby avoiding the decomposition or deterioration of the chemical within the shell of the cartridge in any such time or to materially lengthen the life of the chemical in the cartridge, and facilitating the loading and re-loading of the shells, particularly machine loading.

The invention consists in the novel construction and combinations of parts as set forth in the appended claim.

In the accompanying drawing illustrating the invention:

Figure 1 is a central longitudinal section of the invention.

Figure 2 shows in perspective detail view the chemical container and the cartridge shell.

Figure 3 is a cross section of the chemical container.

Figure 4 is a detail fragmentary view of one end of the chemical container in section.

In this drawing the numeral 1 designates an ordinary cartridge shell such as may be bought in the open market, and having the usual percussion cap 2.

The tear gas chemical 3 before being placed in the cartridge shell is placed within a container, envelop or capsule 4 made of any suitable thin material of equal thinness throughout which will be atomized, disintegrated or burned up at the moment of discharge of the small amount of black or smokeless powder 5 placed in the shell in rear of the chemical envelop as a propellant and to generate sufficient heat in its explosion to immediately destroy the chemical envelop at the time of the discharge of the chemical from the cartridge,

the latter being intended for use in the tear gas gun of the co-pending application of applicant. At the time of such discharge the chemical is of course dispersed forwardly over a wide area and particularly towards the object at which the gun is aimed.

The chemical is placed in the envelop preferably by machinery or a filling device of some kind before the envelop is placed in the primed shell, thereby avoiding hazard to the workman filling the envelops.

The envelop being sealed air tight, prevents the chemical from coming in contact with the metal of the shell, which is one of the usual causes of deterioration.

Among the materials of which the envelop may be made are cellulose, or rubber composition, impregnated paper, etc.

The sealing of the chemical within the container or envelop 4 may be done in any suitable manner, such for instance as by the use of a top disk 6 of the same material as that of the container, sealed around the margin with cellulose acetate, paraffine or sealing wax.

I claim:

In a tear gas cartridge, having a primed shell, a propellant and heat generating filling for the inner end portion of said shell, and a substantially complete filling for the entire outer end portion of said shell consisting of a tear gas chemical and an envelope entirely surrounding said chemical and composed of such readily combustible material of such extreme thinness throughout that it will be immediately consumed as an entirety at the moment of the explosion of the shell in the gun.

In testimony whereof I affix my signature.

WALLACE M. MINTO.
